SOLVENT REFINING PROCESS

Robert E. Manley, Bernard Y. McCarty, and Howard H. Gross, Beacon, N. Y., assignors to The Texas Company, New York, N. Y., a corporation of Delaware

Application February 6, 1935, Serial No. 5,214

8 Claims. (Cl. 196—13)

This invention relates to the treatment of hydrocarbon oil, and particularly to a method of treating hydrocarbon oil, such as mineral oil, with a selective solvent.

5 The invention broadly contemplates a process for solvent refining mineral oil for the production of lubricating oil of high viscosity index, low pour test, and other desired properties and characteristics.

10 The invention comprises extractively treating mineral lubricating oil stock with a selective solvent, such as furfural, for example, wherein the oil is separated into an extract phase containing low viscosity index constituents of the oil together 15 with some constituents of intermediate viscosity index, and a raffinate phase comprising high viscosity index constituents of the oil and retaining some of the extract phase. The two resulting phases are separated, cooled, and centrifuged 20 or settled, to separate all or a portion of the retained matter. The retained matter thus separated from each phase is advantageously returned all or in part to the zone of extraction wherein it is brought into contact with fresh oil 25 undergoing treatment.

In the case of a wax-bearing oil, the raffinate phase, after removal of the retained material, is dewaxed for the production of low pour test lubricating oil.

30 The process of this invention is particularly well adapted to the solvent refining of mineral lubricating oil stock with a solvent of the character of furfural, and wherein the extractive treatment with the selective solvent is effected at 35 temperatures of around 200° F., or in the range from about 150° to 250° F. It has been found that the raffinate phase resulting from extraction at such temperatures may retain an appreciable amount of extract phase material. Similarly, 40 the extract phase may contain a substantial quantity of relatively paraffinic oil of intermediate viscosity temperature characteristics. At the higher temperatures prevailing during such extractions, the raffinate oil tends to retain 45 a substantial amount of the solvent. This retained solvent contains dissolved therein a certain amount of extract phase oil. Also, at such temperatures, the extract phase may comprise substantial amounts of oil of intermediate viscosity index due to the increased solvent power 50 of the solvent at elevated temperatures.

It has been found that by separately removing the extract and raffinate phases from the extraction zone, and subjecting each phase to cooling, 55 and either centrifuging or settling the cooled

phases, the above mentioned retained bodies are largely, if not completely, separated therefrom. In the case of the raffinate phase, it is advantageous to subject it to centrifuging to remove the retained extract phase material, while in the case of the extract phase, it is usually sufficient to cool and subject it to settling or standing only, in order to separate the retained oil of intermediate character.

5 Since the separated materials comprise substantial amounts of the selective solvent liquid, it is desirable to return this material to the extraction zone so that advantage may be taken of the solvent in the extractive treatment of fresh incoming oil. It is contemplated that this separated material may be returned, all or in part, to the extraction zone or, if desired, only that portion separated from the raffinate phase may be so returned. On the other hand, the oil of intermediate character separated from the extract 10 phase alone may be returned to the extraction zone. The latter oil may thus be referred to as a cycle oil. It is thought that substantial benefit 15 results by returning this cycle oil to the extraction zone where its presence tends to favorably influence the subsequent separation of fresh oil into 20 phases respectively rich in paraffinic and non-paraffinic constituents of the oil.

In the case of certain oils being treated as, for 25 example, heavy residual fractions derived from mixed base crudes, it has been found that improved results are realized by centrifuging the raffinate phase resulting from extraction with furfural at high temperatures. These oils contain certain constituents of an asphaltic nature 30 which to some extent remain in the raffinate phase. It has been found that this asphaltic material can be readily removed by centrifuging the raffinate phase, even without prior cooling. The material removed by the centrifuge is of a 35 gelatinous nature and its removal results in a raffinate oil of improved qualities as regards decreased carbon residue, resistance to oxidation, stability of color, etc. as a consequence, subsequent acid treatment of the raffinate oil, which 40 would otherwise be necessary, may be avoided.

45 In order to more clearly describe the invention, reference will now be made to the accompanying drawing illustrating a flow diagram adapted to 50 carry out the process of our invention.

As shown in this drawing, the oil to be treated is drawn from a tank 1 and introduced through a pipe 2 to the lower portion of an extractor 3. It may be necessary to heat the oil prior to introduction to the extractor, in which case the neces- 55

sary heat may be imparted to the oil in the heater 4; otherwise, the heater 4 may be by-passed as indicated.

The furfural is drawn from a tank 5 through a pipe 6 to the upper portion of the extractor 3. As in the case of the incoming charge, it may be necessary to heat the furfural before introduction to the extractor, and in that event, necessary heat may be imparted by means of a heater 7. If 10 no heat is necessary, the heater may be by-passed as indicated. The amount of heat imparted to the incoming solvent and oil is such as to maintain a suitable temperature within the extractor as, for example, within the range from about 150° 15 to about 250° F.

The extractor 3 is of the tower type adapted to effect countercurrent contact between upwardly moving oil and downwardly moving solvent. In order to bring about intimate contact between 20 oil and solvent within the extractor, a suitable packing material, such as Raschig rings, may be provided. On the other hand, mechanical agitating or stirring means may be provided for bringing about the desired degree of contact followed 25 by suitable settling and decanting agitators and settlers may be arranged so as to effect countercurrent solvent action in a number of successive stages.

As a result of this contact between oil and 30 solvent, there results a formation of an extract phase containing the dissolved constituents of the oil, and a raffinate phase comprising the undissolved paraffinic constituents of the oil. As previously mentioned, the extract phase retains a 35 portion of oil of character intermediate as regards viscosity temperature relationship while the raffinate phase retains a small quantity of extract phase material.

The extract phase accumulates in the bottom 40 of the extractor, while the raffinate phase accumulates in the upper portion thereof.

The raffinate phase is removed through a pipe 8 to a cooler 9 wherein it is cooled to a temperature ranging from about thirty to fifty degrees 45 below the extraction temperature. The amount of cooling will depend upon the nature of the oil undergoing treatment. If the oil is substantially wax-free, cooling may be carried to an even lower temperature. On the other hand, in the 50 case of wax-bearing oils, it is desirable to maintain the raffinate phase at a temperature above that at which it would tend to solidify.

The cooled oil is then introduced to a centrifuge or settling chamber 10 to effect separation of the 55 retained extract phase material and other impurities of an asphaltic nature. In some cases, the raffinate phase oil may be introduced directly to the centrifuge or settler without previous cooling. The separated material is conducted to a tank 11. The centrifuged or settled raffinate phase is then conducted to a tank 12, and from there to a still 13 for the removal of any remaining solvent. This solvent removed as a vapor is conducted to a cooler and condenser 20, to which 60 reference is made later.

The solvent-free raffinate oil is then conducted to a tank 14 for such further treatment as may be desired. In the case of a wax-bearing oil, it may be delivered to a dewaxing plant. On the other hand, if it is a wax-free oil, it may, for example, be finished up by clay contact filtration.

The extract phase is removed from the bottom of the extractor 3 through a cooler 15 wherein it is cooled to a temperature substantially below 75 the extraction temperature as, for example,

around thirty or fifty degrees below such temperature. The cooled extract phase is then delivered to a settling chamber 16, wherein the retained oil of intermediate character, insoluble in the solvent at the lower temperature, separates 5 therefrom.

The separated oil is removed to a tank 17. The remaining extract phase is drawn off to a tank 18 and from there to a still 19. The solvent is removed from the oil in the still 19 as a vapor. 10 This vapor is drawn off, along with solvent vapor from the still 13, to a cooler 20 wherein it is cooled and condensed for re-use. The residual extract oil is drawn off from the still 19 to a tank 21 for such further disposition as may be desired. 15

The extract phase material separated from the raffinate phase and accumulating in tank 11, together with the separated or cycle oil accumulating in the tank 17, is delivered by a pump 22 through a pipe 23 to an intermediate point of the 20 extractor 3, wherein it mingles with oil undergoing treatment. If desired, this material may be mixed either with the charge or the furfural prior to introduction to the extractor 3.

On the other hand, the separated liquid from 25 tank 11 may be mixed with fresh furfural entering the extractor 3 or may be introduced thereto at a point where the furfural within the extractor has the same concentration of extract in solution. The cycle oil from tank 17 may be mixed with the 30 fresh charge to the extractor.

By way of illustration, the application of the invention may be described with reference to the treatment of a steam-reduced cylinder stock derived from Pennsylvania crude by countercurrent extraction with furfural at a temperature of around 230° to 250° F., using about five parts of solvent to one part of oil.

The tests on the reduced cylinder stock before 40 treatment will be as follows:

Gravity A. P. I.	25.1
Flash °F.	560
Fire °F.	640
Saybolt universal viscosity—	
At 130° F.	955
At 210° F.	162
Pour °F.	35
Carbon residue, percent.	3.0

When extracted with furfural under the conditions above stated, the oil and solvent will separate into a raffinate phase comprising about 50 15.0% by volume, and an extract phase comprising about 85.0% by volume.

When the above raffinate and extract phases are separated and the solvent removed therefrom by distillation in the presence of steam, the tests on the resulting raffinate oil and extract phase oil will be as follows:

	Raffinate oil	Extract oil
Gravity A. P. I.	26.2	25.6
Flash °F.	580	
Fire °F.	650	
Saybolt universal viscosity—		
At 130° F.	435	
At 210° F.	169	
Carbon residue, percent.	1.35	

If, instead of stripping out the solvent from 70 the raffinate phase, as above mentioned, it is cooled to about 180° F. and centrifuged at that temperature, a quantity of retained extract phase material and some solvent will be separated from the raffinate phase. The separated extract 75

phase material will amount to about 2.3% by volume of the raffinate phase and will comprise a heavy black material, which after removal of the solvent will have a high carbon residue content 5 of around 2.39%.

Similarly, if the extract phase, upon removal from the extraction zone, is cooled and settled at a temperature of about 150° F., oil otherwise retained in the extract phase at the extraction 10 temperature will separate from the mixture. This separated oil is of intermediate character and will amount to about 6% of the original extract phase.

The centrifuged raffinate phase, as well as the 15 oil separated from the extract phase, retains a small amount of furfural which may be removed by distillation. However, if the raffinate phase is to be dewaxed, the retained solvent may remain therein throughout the dewaxing operation. 20 Likewise, where the oil separated from the extract phase is being returned to the extraction zone, it will be unnecessary to remove the retained solvent prior to its return.

The raffinate oil obtained by centrifuging the 25 raffinate phase and the oil separated by cooling the extract phase will, after stripping out any remaining solvent, have the following tests:

30	Centrifuged raffinate	Oil separated from extract phase
Gravity A. P. I.	28.1	27.0
Flash °F.	575	520
Fir. °F.	645	610
35 Saybolt universal viscosity—		
At 160° F.	423	216
At 210° F.	169	94
Carbon residue, percent.	1.30	1.52

It will be observed from the foregoing that centrifuging of the raffinate phase resulted in the 40 removal of a substantial amount of heavy material, namely, 2.3% by volume and having a residual carbon content of 2.39%; also, that by cooling and settling the extract phase, a relatively large amount of oil of intermediate character 45 was separated. This separated material, according to the process of our invention, is returned to the extraction zone, all or in part, and mixed with fresh oil undergoing treatment.

The remaining extract phase may be stored 50 for such further disposition as may be desired. The centrifuged raffinate oil, in the case of a wax-bearing oil, is then mixed with a suitable dewaxing solvent mixture, such as a mixture of acetone and benzol, for example, and dewaxed in the usual manner.

The process of this invention is not necessarily restricted to extraction with a specific solvent such as furfural, for it is contemplated that other 60 selective solvents having the essential selective action of furfural as between constituents of the oil of differing viscosity indices may be employed. Thus, the process of this invention is particularly applicable where the solvents employed are used at temperatures considerably elevated above normal atmospheric temperature. The raffinate and extract phases obtained when extracting with such solvents as nitrobenzene, aniline and crotonaldehyde may be advantageously treated 65 in accordance with the process of our invention.

Furthermore, the process of this invention is not limited to the treatment of any particular type of hydrocarbon oil or petroleum fraction. It is adapted to the treatment of either distillate 75 or residual fractions of petroleum.

Moreover, it is contemplated that, as regards the specific manner in which the invention is practiced, temperatures and proportions of solvent may vary from those mentioned above. In the case of dewaxed oils, or relatively less viscous oils, lower extraction temperatures may be employed. The extraction of the oil with the selective solvent may be carried out in either a continuous or stage countercurrent operation. Extraction by the batch or multiple batch method 10 of operation may also be employed.

Obviously, many modifications and variations of the invention, as hereinbefore set forth, may be made without departing from the spirit and scope thereof, and therefore only such limitations 15 should be imposed as are indicated in the appended claims.

We claim:

1. In the refining, with a selective solvent, 20 of a heavy lubricating oil stock containing residual carbon-forming bodies which form with the solvent a small amount of material of a gelatinous nature and which is difficultly removable from the resulting raffinate, the method comprising extracting the oil with a solvent comprising furfural at a temperature of around 200° F., forming an extract phase containing low viscosity index constituents of the oil and a raffinate phase containing high viscosity index constituents and a substantial amount of said 30 gelatinous material, removing the raffinate phase, and centrifuging the raffinate phase while at an elevated temperature not substantially below the extraction temperature to remove the gelatinous material contained therein. 35

2. In the refining, with a selective solvent, of a heavy residual lubricating oil stock containing residual carbon-forming bodies which form with the solvent a small amount of material of a gelatinous nature and which is difficultly removable 40 from the resulting raffinate, the method comprising extracting the oil with a solvent comprising furfural at a temperature of around 200° F., forming an extract phase containing low viscosity index constituents of the oil and a raffinate phase containing high viscosity index constituents and a substantial amount of said gelatinous material, removing the raffinate phase, and centrifuging the removed raffinate phase in the presence of all its retained solvent while at an 50 elevated temperature of around 180°-200° F. to remove the gelatinous material contained therein. 45

3. The method of refining mineral lubricating oil comprising extracting the oil with an extraction solvent at a temperature in the range 150° to 250° F., forming an extract phase containing low viscosity index constituents of the oil dissolved in the bulk of the solvent and a raffinate phase comprising high viscosity index constituents of the oil mixed with a small amount of heavy extract, removing the two phases, centrifuging the removed raffinate phase at a temperature not substantially below the extraction temperature and thereby separating retained 60 heavy extract material, reducing the temperature of the extract phase to separate therefrom oil of intermediate viscosity index, and removing the oil of intermediate character so precipitated. 65

4. The method of refining mineral lubricating oil comprising extracting the oil with furfural at a temperature in the range 150° to 250° F., forming an extract phase containing low viscosity index constituents of the oil dissolved in the 75

- bulk of the solvent and a raffinate phase comprising high viscosity index constituents of the oil mixed with a small amount of heavy extract, removing the two phases, centrifuging the removed raffinate phase at a temperature not substantially below the extraction temperature and thereby separating retained heavy extract material, reducing the temperature of the extract phase substantially below said extraction temperature to separate therefrom oil of intermediate viscosity index, and removing the oil of intermediate character so precipitated.
5. The method of refining mineral lubricating oil comprising extracting the oil with furfural at a temperature in the range 150° to 250° F. in an extraction zone, forming an extract phase containing low viscosity index constituents of the oil dissolved in the bulk of the solvent and a raffinate phase comprising high viscosity index constituents of the oil mixed with a small amount of heavy extract, removing the two phases, centrifuging the removed raffinate phase at a temperature not substantially below the extraction temperature and thereby separating retained heavy extract material, reducing the temperature of the extract phase substantially below said extraction temperature to separate therefrom oil of intermediate viscosity index, and removing the oil of intermediate character so precipitated, and returning separated oil of intermediate character to aforesaid extraction zone.
6. The method of refining mineral lubricating oil comprising extracting the oil with an extraction solvent, forming an extract phase containing low viscosity index constituents of the oil dissolved in the bulk of the solvent and a raffinate phase comprising high viscosity index constituents of the oil mixed with a small amount of retained heavy extract oil dissolved in extraction solvent amounting to about 2% of the raffinate phase and suspended in said raffinate phase, removing the two phases, and without substantially altering the solvent composition, centrifuging the removed raffinate phase at a

temperature substantially the same as the extraction temperature and thereby separating the small amount of retained heavy extract material, without separation of the raffinate into liquid phases.

5

7. The method of refining mineral lubricating oil comprising extracting the oil with an extraction solvent, forming an extract phase containing low viscosity index constituents of the oil dissolved in the bulk of the solvent and a raffinate phase comprising high viscosity index constituents of the oil mixed with a small amount of retained heavy extract oil dissolved in extraction solvent, removing the two phases, centrifuging the removed raffinate phase at a temperature of around 180 to 200° F. and thereby separating retained heavy extract material, reducing the temperature of the extract phase substantially below said extraction temperature to separate therefrom oil of intermediate viscosity index, and removing the oil of intermediate character so precipitated.

10

8. The method of refining mineral lubricating oil by selective solvent extraction comprising extracting the oil with a selective solvent, forming an extract phase containing low viscosity index constituents of the oil dissolved in the bulk of the solvent and a raffinate phase comprising high viscosity index constituents of the oil and containing a small amount of tarry material dissolved in solvent amounting to around 2% or more of the raffinate phase, removing the raffinate phase, and centrifuging the removed raffinate phase in the presence of all its retained solvent and while at an elevated temperature of the order of 150° F. and not substantially below the temperature at which the oil was extracted with the selective solvent thereby to remove said small amount of tarry material without separation of the raffinate into liquid phases.
